**PORTABLE RADIO DUAL TUNING FACE
INDICATOR PLATE**

Maurice D. Katz, 35 Broadway, Lawrence, N.Y. 11559

Filed May 18, 1971, Ser. No. 144,700

Term of patent 14 years

Int. Cl. D14—03

U.S. Cl. D26—1

FIG.1

FIG.2

FIG. 1 is a top plan view of a portable radio dual tuning indicator face plate showing my new design; and

FIG. 2 is a perspective view with the face indicator plate installed in a radio.

The broken lines are shown for illustrative purposes only.

I claim:

The ornamental design for a portable radio dual tuning face indicator plate, substantially as shown and described.
